(57) **CLAIM**

The ornamental design for a sleep aid garment, as shown and described.

DESCRIPTION

FIG. 1 is a perspective rear view of a sleep aid garment, showing my new design;

FIG. 2 is a perspective front view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines shown throughout the views represent the portions of the design, which form no part of the claim.
